UNITED STATES PATENT OFFICE.

CHARLES PERILLAT, OF BOSTON, MASSACHUSETTS, ASSIGNOR, BY DIRECT AND MESNE ASSIGNMENTS, TO KITSON HYDROCARBON HEATING AND INCANDESCENT LIGHTING COMPANY, OF PHILADELPHIA, PENNSYLVANIA, A CORPORATION OF WEST VIRGINIA.

HYDROCARBON-LAMP.

SPECIFICATION forming part of Letters Patent No. 760,560, dated May 24, 1904.

Application filed September 12, 1899. Serial No. 730,229. (No model.)

To all whom it may concern:

Be it known that I, CHARLES PERILLAT, a citizen of France, residing at No. 2 East Cottage street, Boston, in the county of Suffolk and State of Massachusetts, have invented an Improvement in Hydrocarbon - Lamps, of which the following description, in connection with the accompanying drawings, is a specification, like characters on the drawings representing like parts.

This invention relates to a hydrocarbon-lamp of that class in which an oil is vaporized by the heat from the burners, and the vapor thus formed is admixed with air and supplied to the burners. Lamps of this general class as now constructed and known to me are provided with a vaporizing-tube having an oil-inlet near one end and a substantially small vapor-outlet in the opposite end, with which coöperates a needle-valve, by means of which the amount of the vapor issuing from said outlet may be controlled and by means of which the said outlet may be kept clean and free from carbon deposits.

Lamps constructed as above described are defective in that the needle cannot be removed while the lamp is in operation, because the oil supplied to the vaporizer will leak out of the lamp and drop therefrom when said needle is removed, which is objectionable on account of the damage which might be done thereby and also on account of the disagreeable odor of the oil or hydrocarbon.

My present invention has for its object to improve the lamps of the class described so that the cleaning and regulating needle may be removed and replaced by a new one while the lamp is in operation without danger of leakage of oil or of breaking the needle.

Figure 1 is a vertical section of a hydrocarbon-lamp embodying this invention, and Fig. 2 a detail in vertical section through the vaporizing-tube on an enlarged scale.

This invention is herein shown as embodied in what is known as a "hydrocarbon arc-lamp," provided with a casing or framework

composed of a metal cylinder or ring *a*, a reflector *b*, secured thereto, a hood *c*, supported above the said ring and reflector by arms or legs *e*.

The cylinder or casing *a* has detachably secured to it, as by suitable screws, (not shown,) a metal band *f*, which supports a glass or other globe *g*, which may be secured to said band in any suitable or desired manner. The operative parts of the lamp proper are located within the cylinder *a* and globe *g* and consist, essentially, of burners *h*, only one of which is shown in Fig. 1, erected upon a chamber *i*, connected by pipes *j*, only one of which is shown, with a mixing-chamber *k*, suitably fastened to the cylinder *a* and having extended up into it a pipe *m*, connected to a pipe *n*, constituting an air-supply pipe which extends through the casing *a* and communicates with the atmosphere below the reflector. The air-supply pipe *n* has extended up into it, preferably in line with the pipe *m*, the detachable cap *2* of a tube *3*, constituting a vaporizing-chamber, the said cap having a substantially small discharge orifice or opening *4*. (See Fig. 2.) The tube *3* is detachably secured at its lower end to a fitting *5*, provided with an oil-inlet passage with which communicates an oil-inlet pipe *7*, leading to a suitable source of supply. The fitting *5* has extended through it a substantially long needle *8*, which coöperates with the discharge-orifice *4* for the purpose of regulating the supply of vapor to the burners and also for the purpose of clearing or freeing said orifice from any hydrocarbons which might be deposited on the walls thereof. This invention has for its object to avoid leakage of oil down past the needle out of the fitting and also to dispense with the use of packing material within the fitting, and this result may be accomplished, as shown, by means of a substantially small tube *10*, having its lower end secured liquid-tight within the fitting *5* below the mouth of the inlet-pipe *7* either by screw-threads, as shown, or by brazing. The tube *10* thus securely cuts off the vaporizing-

chamber surrounding the said tube from the opening in the bottom of the fitting, through which the needle is passed, so that the said needle may be entirely removed from the fitting without danger of oil admitted into the vaporizing-chamber passing out of said fitting through said opening. For this reason broken or damaged needles may be replaced by new ones while the lamp is in operation without any damage or inconvenience resulting therefrom, as the construction prevents leakage of oil, and the change can be made before the vapors have an opportunity to escape. The tube 10 is preferably made of sufficient length so that its upper end projects into the cap 2 and forms therewith a substantially small or narrow annular port 15, (see Fig. 2,) which connects the vaporizing-chamber 12 with a passage 16 in the cap and from which passage the discharge-orifice extends. The passage 16 is preferably made tapering, so that the needle may be directed into the discharge-opening 4 without danger of breaking the fine point of the needle.

25 The needle 8 is adjustably secured to a nipple 20, extended from the bottom of the fitting 5 by a nut 21, having a yoke 22, which is split at its bottom, and the said needle is clamped between the split portion of the yoke, as by screws 23 24. As an additional safeguard against leakage of oil past the needle the nipple 20 may be provided with a threaded socket 25 for the reception of suitable packing material, (not here shown,) which may be compressed about the needle by a hollow adjusting-screw 26, which, it will be noticed, is accessible from outside the lamp and which therefore enables the packing in the socket to be adjusted while the lamp is in operation, if required.

40 The vaporizer element as an entirety, including the outer tube or casing 3, its nipple or closing device 2, having the jet-orifice, the inner tube or casing, the needle-valve, and valve-rod, is secured to the burner by means of the threaded sleeve at 40, adapted to engage with the collar or support, said collar or support being carried by the burner-frame, and when desired this part of the structure 45 can be readily detached for cleaning, repairing, or fitting of parts.

45 In the operation of the lamp the hydrocarbon oil admitted into the chamber 12 is vaporized therein by the heat from the burners, and the said vapor rises in said chamber and passes through the port 15 into the passage 16, from which it passes into the air-pipe *n* and thence through the pipe *m* into the mixing-chamber *k*. The vapor passing through 50 the pipe *m* draws pure air through the pipe *n*, and the said air and vapors are mixed in the chamber *k*. This mixture is then conducted through the pipes *j* to the burners, where it is consumed, and the products of combustion 55 rise and pass through the casing *a* into the

chamber 30, formed by the hood, and from this chamber the consumed gases pass into the atmosphere above the reflector. It will thus be seen that the air-supply for the lamp is separated by the reflector from the immediate vicinity and vitiating influence of the consumed gases, which results in a more perfect combustion at the burners and also avoids the disagreeable effects of imperfect combustion of hydrocarbons.

75 The burners *h* may be lighted by means of alcohol placed in a depression or cavity 31 in the top wall of the chamber *i*, and which is ignited by a flame inserted up through a tube 35, attached to the wall of the burner-chamber *i*. The vaporizing-tube 3 is extended up through the burner-chamber *i* and is detachably secured thereto by a threaded collar or nut 40, fast on said tube.

80 It will be seen that the jet-orifice from which the vapor finally escapes under pressure into immediate contact with the air (with which it is to mingle in the mixing-chamber) is directly controlled by the needle-valve and that the vapor escapes from this orifice by 85 traveling in the direction toward which the needle points, it, in fact, moving along and around the needle-point as it impinges upon the air. It is at this jet-orifice of final escape for the vapor that there is a tendency for carbon bodies to deposit and accumulate, and these must be removed in order to not only permit the escape of vapor, but also to accurately and delicately control the jet. Attempts have been heretofore made to provide 90 this relative arrangement of the jet-orifice, the air-supply duct, and the mixing-chamber by employing a vertically-arranged needle-valve in conjunction with an upwardly-directed jet-orifice for the escape of the vapor; but, as 95 herein described, the earlier constructions aiming at this have been of such design that if the needle should be withdrawn to allow the escape of the deposits or for the repairing or replacing of the needle there was an escape of 100 oil. This I prevent by so constructing the vaporizer as to have a liquid-receiving and vapor-generating chamber with an outer wall or casing and an inner wall or casing connected tightly to the outer one at the bottom 105 and situated around the needle and extending upward to such point as to prevent the oil from coming into contact with the needle and from escaping when the needle is withdrawn. The 110 needle can be manipulated in any way desired 115 when the lamp is in operation either for cleaning the jet-orifice, for regulating the jet, or for completely withdrawing it. It will be further seen that the guard-tube or inner casing has an interior chamber of a diameter considerably larger than that of the needle-valve and providing a chamber directly below the jet-orifice, which receives the carbon or other 120 deposits that may be released from the walls of the jet-orifice, this chamber being inde-

125 130

pendent of the liquid-receiving space, so that provision is made both for keeping the orifice clean and for preventing the introducing of impurities into the vaporizing or liquid chamber; but the other features of construction and operation, it will be understood, are not dependent upon having the inner guard-tube or casing of any particular interior diameter, as the principal purpose can be met so long as it is large enough to avoid the liquid from contacting with the valve or valve-rod, nor are the novel features of the invention to be limited to any precise position of the longitudinal axis of the vaporizing-tube in relation to the vertical or horizontal. I herein show this tube and the valve and valve-rod as supported on vertical lines and for convenience describe the vaporizer as below the mixing-chamber and the vapor-jet orifices as being upwardly directed; but it will be readily seen that if the positions of the several parts relative to each other be retained the entire system of parts can be placed so as to have the longitudinal axis of the vaporizer horizontal or inclined without departing from the characteristic matters.

I claim—

1. In a lamp of the class described, the combination of the following instrumentalities, viz: a fitting provided with a liquid-inlet port, a vaporizing-tube secured at one end to said fitting and provided in its opposite end with a substantially small discharge-orifice or vapor-outlet, a smaller tube within the vaporizing-tube and secured liquid-tight to said fitting beyond said oil-inlet, and a needle-valve inserted through said fitting into and through said smaller tube and coöperating with the discharge-orifice in the end of the vaporizer-tube opposite to said fitting, for controlling the passage of vapor from within the vaporizing-tube out therefrom through said discharge-orifice and for cleaning said orifice, said inner tube being arranged to protect the needle-valve from contact with the liquid, when the lamp is in operation, substantially as described.

2. In a lamp of the class described, the combination of the following instrumentalities, viz: a fitting provided with a liquid-inlet port, a vaporizing-tube secured to said fitting, a cap on the free end of said tube provided with a substantially small discharge-orifice and with a tapering passage leading thereto, a smaller tube within the vaporizing-tube and secured liquid-tight to said fitting at its lower end below the said liquid-inlet, an extension on said fitting provided with a threaded socket and with screw-threads on its exterior, a hollow screw inserted into said threaded socket and accessible from outside of said fitting, a needle extended through said hollow screw and fitting into said inner tube, and a nut engaging said extension and to which said needle is secured, substantially as described.

3. In a vapor-burner of the class described,

the combination of the burner, a mixing-chamber, a liquid-supply pipe, a vaporizer between the liquid-supply pipe and the mixing-chamber, said vaporizer having an outer compartment and an inner compartment and a vapor-jet orifice directly over the inner compartment, the outer compartment communicating with the liquid-supply pipe, the inner compartment being cut off from direct communication with the said liquid-supply pipe, and the two compartments communicating with each other at points in the vapor-generating region remote from the liquid-entrance whereby the liquid is prevented from entering the inner compartment, a needle-valve for said orifice, and a valve-rod passing through said inner compartment and held out of contact with the liquid, substantially as set forth.

4. In a vapor-burner of the class described, the combination of the burner and liquid-supply pipe, a vaporizer having an outer casing with an upwardly-directed vapor-jet orifice, and the inner tube or casing providing a liquid-receptacle outside of the inner tube, and also a vapor-holding retort-chamber adjacent to the jet-orifice, a mixing-chamber above said orifice, a vapor-conductor having a duct leading from said orifice to said mixing-chamber, an air-conductor supplying air to the said vapor-duct at points above the jet-orifice, a vertically-arranged needle-valve having a valve-rod situated within the inner casing of the vaporizer and extending from points below the liquid-receptacle to the said jet-orifice and detachable from the burner without releasing oil, said parts being arranged substantially as set forth to cause the vapor to pass directly upward with the air into the mixing-chamber and to prevent the liquid from contacting with the valve-rod.

5. In a vapor-burner of the class described, the combination of the burner and mixing-chamber, a conductor having a vapor-duct extending from the mixing-chamber to the burner, an air-supplying conductor, a vaporizer below the mixing-chamber having a liquid-port and a jet-orifice directed through the air-duct toward the mixing-chamber, a needle-valve for said jet-orifice having a valve-rod extending through the vaporizer, and a guard-tube in the vaporizer around the needle-valve arranged to prevent the liquid from contacting with the valve, said parts being disposed substantially as set forth whereby the vapor-jet as it escapes from said orifice impinges directly upon the air in its passage toward the mixing-chamber whereby the deposits in the orifice can be dislodged by the valve, and whereby the valve can be withdrawn without escape of oil.

6. In a vapor-burner, the combination with the mixing-chamber, the burner and the air-inlet tube communicating with the mixing-chamber, of the vaporizing element having an outer tube with a vapor-jet orifice at one end,

and an inner tube tightly connected to the outer tube at points remote from the jet-orifice whereby there is formed an outer compartment and an inner compartment, the outer 5 compartment communicating with the said jet-orifice and having an inlet-port for fluid hydrocarbon at points between the vapor-jet orifice and the points where the tubes are tightly connected, a needle-valve in the said 10 jet-orifice, and the valve-rod passing through the inner tube and protected by the latter from contacting with said fluid, substantially as set forth.

7. In a vapor-burner having a mixing- 15 chamber an air-supply pipe and a burner, a vaporizer having an outer tube 3, the nipple or closing device 2 with a jet-orifice and secured to said tube 3, the inner tube 10, means for securing the inner tube to the outer tube 20 with a fluid-tight joint, and the outer tube having a port for conducting fluid at points between said joint and the jet-orifice, a needle-valve for said orifice, and a needle-valve passing through the inner tube, substantially 25 as set forth.

8. In a vapor-burner, the combination with the mixing-chamber, the burner and the air-inlet tube for the mixing-chamber, of the vaporizing element attached to the aforesaid 30 parts and bodily separable therefrom, said vaporizing element having a fluid-receiving

tube 3, a nipple or closing plug 2 secured thereto and provided with a jet-orifice communicating with the chamber in the said tube, a needle-valve for the said orifice, a valve-rod 35 extending through the transverse planes of the receiving-chamber in the said tube, and means surrounding said valve-rod and interposed between it and the fluid in the said tube, said valve and valve-rod being detachable 40 from the vaporizer, substantially as set forth.

9. In a vapor-burner of the class described, the combination of the burner, the mixing-chamber connected with the burner, a liquid-supply pipe, a vaporizer between said pipe 45 and mixing-chamber and having a jet-orifice for the escape of vapor under pressure, a vertically-arranged needle-valve with a valve-rod passing through the vaporizer, and a guard-wall around the valve-rod adapted to prevent 50 the contacting of liquid therewith and having a chamber below the jet-orifice independent of the liquid-receiving chamber and adapted to receive the deposits dislodged from the jet-orifice walls, substantially as set forth. 55

In testimony whereof I have signed my name to this specification in the presence of two subscribing witnesses.

CHARLES PERILLAT.
